UNITED STATES PATENT OFFICE

OTTO A. DRENGWITZ, OF JEANNETTE, PENNSYLVANIA

GAME

Application filed June 16, 1928. Serial No. 285,887.

This invention relates broadly to games and is for a game wherein a game piece may be mechanically moved along a game board by means of an actuating mechanism or impeller of novel construction.

According to my invention, game pieces may be moved along circular, polygonal, sinuous or winding pathways by an impeller which can be operated from a driving means 10 conveniently located on the game board.

There may be confined with the impeller for moving the game pieces, various indicators and coordinated mechanisms for producing certain desired action. For instance, 15 the invention may be embodied in a baseball game where the action of some of the players is mechanically represented, or in racing games, where various hazards of the race may be encountered.

20 In the accompanying drawings I have shown certain present preferred embodiments of the invention wherein

Figure 1 is a plan view of a game board with a portion removed;

25 Figure 2 is a plan view of a portion of the game board shown in Figure 1 but having the top or playing surface removed in order that the operating parts may be seen, the parts being in a different operative position than 30 shown in Figure 1;

Figure 3 is a cross section on the line III—III of Figure 1, portions being cut away;

Figure 4 is a detail to enlarged scale of a 35 portion of the device shown in Figure 2;

Figure 5 is a detail view showing the operation of the impeller on a movable playing piece;

40 Figure 6 is a top plan view of a portion of the mechanism shown in Figure 5 but with the figure of the player removed for simplicity;

Figure 7 is a detail view showing the operative connection of one of the playing pieces 45 to its actuating mechanism;

Figure 8 is a plan view of the play indicator shown in Figures 1 and 2;

Figure 9 is a plan view of a modified form 50 of game board with a portion of its playing surface removed;

Figure 10 is a cross section on the line X—X of Figure 9, a portion being cut away; Figures 11 and 12 are detail views of a modified form of game piece, Figure 11 being a side elevation and Figure 12 a front view; 55 and

Figure 13 is a detail view of the playing piece representing the batter.

Referring more particularly to the drawings and to the embodiment of the invention 60 shown in Figures 1 to 8, inclusive, reference numeral 2 designates generally a game board having side walls 3, a bottom 4 and a top or playing surface 5. Strips 6 are fastened to the interior of the side walls and support the 65 bottom 4 and the top 5, which are formed of sheet metal. Connected to the bottom 4 is an upwardly projecting member 7 having formed as a part thereof a pair of vertically 70 extending walls 8. The inner of the walls 8 is of less height than the outer as shown in Figure 3 for a purpose to be presently described. The walls 8 together with the member 7 form a channel which is substantially 75 closed on three sides and which extends in a curve, as shown in Figures 1 and 2, substantially underlying a representation on the board of the base paths of a baseball diamond. The top 5 of the board has a slot 9 extending completely around the base paths of the 80 diamond, so that the top is in fact divided into an outer portion 10 and an inner portion 10^a, which inner portion 10^a is fastened to the bottom 4 by screws 11. The outer portion 10 of the top is also fastened to the bottom 4 by screws 12. The outer wall 8 is 85 reversely curved at 13, as shown in Figures 1 and 2, to accommodate the impeller, to be presently described.

Suitably journalled at 14 on the bottom 4 is a shaft 15 to which outside a side wall 3 of the board is keyed a pinion 16. Journalled in the side wall 3 adjacent the shaft 15 is a stud shaft 17 to which is keyed a gear 18 meshing with the pinion 16 and having affixed 90 thereto an operating handle 19.

Connected to the shaft 15 is an impeller 20 having a substantially helical portion 21. This impeller, as shown in the preferred embodiment, comprises a flexible metal coil. 100

The coil 20 is resilient and partakes of the nature of an ordinary coil spring. It extends from the shaft 15 into the channel formed by the walls 8 and the member 7 being guided adjacent the shaft along the reversely curved portion 18 of the outer wall. The impeller is of such a size as to substantially fill the channel, although it is loose enough to permit of rotation substantially about its axis.

Rotation of the gear 18 by means of the operating handle 19 transmits, through the pinion 16 and the shaft 15, a rotational movement to the impeller 20. By reason of its flexibility, such rotation is possible despite the curves in the channel at the bases of the diamond. By reason of the nature of the impeller and its containing channel, its rotation is impeded at points along its length, which impedance tends to slow it up at such points while permitting an added stress to be built up in the impeller between a point of impedance and the point at which the force is applied thereto. When the stress so imparted to the impeller reaches a certain value, it will be great enough to overcome the impedance and to cause rotation of the impeller at an impedance point at an increased speed so as to tend to relieve it of unequal stresses. Thus if the operating handle 19 be continuously rotated at a constant speed, there will be produced in the impeller a non-uniform or jerky motion. A given point of the impeller will move at a normal speed for an increment of time, following which it will move at a reduced speed due to the impedance, and subsequently it will move at an increased speed due to overcoming of the impedance as above described. This non-uniform or jerky motion of the impeller is made use of as will be presently described.

Journalled in the board at a point corresponding to the pitcher's box is a vertical shaft 22 having a non-circular upper extremity 23. Rigidly fixed to the shaft 22 is a link 24 having a lateral extension 25 to which is attached a coil spring 26, such spring being dead-ended at its opposite end at 27 to the bottom 4.

Pivoted to the bottom 4 at 28 is a link 29 to which at its opposite end is pivoted a lever 30 at a point 31 intermediate its ends. One end of the lever 30 is pivoted to the link 24 at 32 and the other end of the lever is pivoted to a slide 33 at 34. The slide 33 is provided with two longitudinal slots 35 embracing pins 36 connected to the bottom 4.

Journalled in the board at a point corresponding to the batter's position is a vertical shaft 37 having a non-circular upper extremity 38. Rigidly fixed to the shaft 37 is a link 39 having a longitudinal slot 40 embracing a vertically extending pin 41 on the slide 33. Loosely pivoted about the shaft 38 at a point intermediate its ends is a lever 42 to

which at one end is pivoted at 43 a link 44. At its opposite end the link 44 is pivoted to an upstanding post 45 connected to the slide 33 and having a non-circular upper extremity 46. At its opposite end the lever 42 is pivoted at 47 to a dog leg link 48 having at its opposite extremity an upstanding pin 49.

The vertical shafts 22 and 37 extend up through circular holes in the top 5. The post 45 and the pin 49 extend up through longitudinal slots in the top to permit of their motion substantially in the direction of the length of the slide 33.

The shafts 22 and 37 and the post 45 are adapted to receive over their non-circular upper extremities playing pieces representing the pitcher, batter and catcher, respectively. The piece representing the catcher which fits over the post 46 serves as a means whereby a person playing the game may operate the mechanism above described. Assuming the parts to be in the position shown in Figure 2, to which position they are resiliently urged by the spring 26, the player grasps the piece representing the catcher and moves it to the left, viewing such figure, until the parts assume the position shown in Figure 1. In this position the spring 26 is under tension and is tending to restore the parts to the position shown in Figure 2 by movement generally to the right viewing such figure.

Movement of the parts generally toward the left as above described causes the shaft 22 upon which the piece representing the pitcher is mounted to rotate throughout a small angle in a clockwise direction. This movement is intended to simulate the pitcher's windup. In Figure 7 is shown a playing piece 50 representing the pitcher having a base 51 in which is a vertical slot 52 of a size adapted to receive the non-circular extremity 23 of the shaft 22. A set screw 53 is provided for securely holding the piece on the shaft. The playing pieces above described representing the batter and catcher are constructed generally similarly to the piece representing the pitcher, except that appropriate figures are used for the respective pieces. The piece representing the batter is slightly modified, however, as will be presently described.

Movement of the parts generally toward the left also causes rotation of the shaft 37, and consequently of the playing piece representing the batter which is mounted thereon, throughout a small angle in a clockwise direction. The batter is represented as being right-handed, so that rotation of the piece in the manner described is intended to simulate drawing back of the bat by the batter preparatory to striking at a pitched ball.

At the same time as the pitcher is in position to pitch the ball and the batter is in position to strike at it, the catcher is in a posi-

tion some distance behind the home plate intending to simulate his position when giving the signals to the pitcher. Also at the same time the pin 49, as shown in Figure 1, is in its extreme right hand position and adapted to be moved to the left upon release of the piece representing the catcher by the person playing the game. A ball of suitable size intended to represent a baseball is placed in the slot in the top of the board which contains the pin 49 and against the pin. The ball must, of course, be large enough not to pass through the slot and small enough so that movement of the pin will project it over the surface of the board toward the home plate. All of the parts as thus described are therefore in position for commencement of a play by a pitched ball.

The person playing the game quickly releases the piece representing the catcher so that the parts under action of the spring 26 are caused to move quickly to the right. This movement causes the piece representing the pitcher to be rotated in a counter-clockwise direction, simulating pitching the ball, the piece representing the batter to be rotated in a counter-clockwise direction, simulating striking at the ball, and the piece representing the catcher to be moved to the right, simulating adjusting his position for receiving the pitched ball. At the same time the pin 49 is moved sharply to the left projecting the ball from the pitcher's box across the home plate. The piece representing the batter, shown in Figure 13, has an extension 97 just above the level of the top of the board which is moved into the path of the ball by the rotation of the piece, simulating the hitting of the ball by the bat, whereupon the ball is projected out over the board as is the case with a batted ball in a baseball game.

The cycle of events above described is repeated each time a ball is pitched and, when taken in combination with the elements and steps yet to be described, constitutes the playing of the game.

The slide 33 has a lateral extension 54 which in turn has a lateral extension 55. The end 56 of the extension 54 lies between the top of the board and a guide 57 which is secured to the board but has a portion 58 raised slightly thereabove to permit of reception of the end 56. At its outer extremity the extension 55 is provided with an upstanding leg 59.

Journalled in the board at 60 is an indicating disc 61 having upon its under surface a gear 62. Upon reciprocation of the slide 33, and consequently the lug 59, such lug meshes with a tooth of the gear causing the latter, upon movement of the lug to the right, to be rotated at a considerable speed.

The indicating disc 61 is provided with indicia disposed at different distances from its center. The top 10 is provided with slots

63 overlying the indicia and exposing each throughout a portion of the periphery of the disc. The indicia indicate the fate of the batter upon striking at a pitched ball. It will be seen that each time that the piece representing the catcher is drawn to the left by the person playing the game and then permitted to snap to the right, as above described, the lug 59 engages a tooth of the gear 62, thereby rotating the disc 61 in a clockwise direction. The lug 59 moves far enough to the right to pass out of mesh with the gear 62 so that the disc will continue its rotation until it comes to rest by reason of the friction at its pivotal mounting. At the time when the disc finally comes to rest, the portions of the indicia which are exposed through the slots 63 indicate the fate of the batter, such as whether he had a strike or a ball or made a hit or grounded out, etc. Thus the indicating disc 61 determines upon the pitching of each ball what takes place with regard to the batter. This indicator, therefore, determines in what instances a batter becomes a base runner.

The indicia on the disc 61 may comprise different colored arcuate portions 98, as shown in Figure 8, the respective colors being referred to an appropriate chart to determine the fate of the batter.

The actuator 20 serves as a means by which the pieces representing base runners are moved around the base paths. When according to the indicator 61 a batter becomes a base runner, a playing piece 64 (Figure 5) representing a base runner is placed in operative engagement with the actuator along the path from home plate to first base. The playing piece 64 has a flat base 65 and from which extends downwardly a projection 66 of such shape as to fit between successive convolutions of the actuator, as clearly shown in Figure 5. The base 65 rests upon the top of the board and the projection 66 passes through the slot 9 to engage the actuator. Upon turning of the operating handle 19 and consequent rotation of the actuator, the playing piece 64 will be moved in the direction of the axis of the actuator in a manner which is apparent.

Closely mounted about the shaft 22 is an indicating disc 67 having a large circular central opening 68. This opening is merely to permit the passage of the shaft 23 therethrough and does not serve as a bearing or centering means for the indicating disc 67. As shown in Figure 3, the disc rests at its edges upon the inner upright wall 8. It is provided at its periphery with teeth 69. These teeth are not equally spaced about the entire periphery of the disc but are closer together at portions thereof than at other portions. The purpose of this provision will be presently made apparent.

The teeth 69 of the indicating disc 67 en-

130

gage between the successive convolutions of the actuator 20 as shown in Figures 1 to 4, inclusive. Upon rotation of the actuator, therefore, the convolutions thereof bear 5 against the edges of the teeth of the indicating disc and cause it to move in a counter-clockwise direction, viewing Figure 2, as indicated by the arrow. If the motion of the actuator were uniform throughout at all 10 times and the teeth of the indicating disc were equally spaced about its entire periphery, the rotational movement of the disc would be at a constant speed. However, as above explained, the actuator moves with a non-uniform 15 or jerky motion. Furthermore, the disc is provided with teeth which are not equally spaced about its entire periphery. Consequently, when a portion of the disc having teeth more closely spaced is in contact 20 with the actuator, the disc will move more slowly than when a portion of it having teeth less closely spaced is in contact with the actuator. The unequal spacing of the teeth 25 of the indicating disc when combined with the irregular or jerky motion of the actuator, renders the rotation of the indicating disc quite irregular and uncertain. This is a feature intended to add to the hazards and uncertainties of the game.

30 The indicating disc 67 is provided with indicia spaced at different distances from its center and generally similar to the indicia of the indicating disc 61. Similarly the top of the board has slots 70 adapted to reveal the 35 indicia as do the slots 63 above the indicating disc 61. There are preferably four slots, one for each base. The indicia on the indicating disk 67 determine the fate of a base runner once he has become such, by virtue of the indicating disc 61. Thus the disc 67 indicates 40 whether a player is "safe" or "out" at first base, whether he shall continue to second base, when he shall move to third, when he is safe or out at any base, etc.

45 At each play the base runner or runners are advanced by turning the operating handle 19, the indicating disc 67 being at the same time rotated, as above described. Its action being uncertain, it is not possible for the players 50 to predict, by reason of any previous knowledge of the board, what fate will come to any given runner or runners. The amount which the player turns the crank to move the players after each play involving movement of a 55 base runner is determined by the indicia appearing through slots 70 at the time a base runner reaches a base.

In Figures 9 and 10 is shown an embodiment of certain of the broad features of my 60 invention in a somewhat different type of game. In these figures is shown a board 71 having side walls 72, strips 73, a bottom 74 and a top 75. The board is held in assembled relationship by means of nuts and bolts 65 76. Channels are provided on the bottom 74

which are generally similar to the channels of the embodiment of the invention shown in Figures 1 to 8, inclusive, and serve the same purpose, namely to contain the impellers. In this modification, however, there are two impellers 77 and 78 actuated by operating handles 79 and 80, respectively, through suitable mechanism substantially as in the embodiment above mentioned.

70 Each impeller has associated with it an indicating disc 81 having gear teeth 82, such gear teeth meshing with the impeller whereby the indicating discs are rotated when the impellers are rotated. The top 75 of the board has slots 83 through which suitable indicia 75 80 on the indicating discs may be viewed.

The game of the modification shown in Figures 9 and 10 is a contest between two pieces 84 and 85 representing aeroplanes but having projections 86 substantially identical with the projection 63 of the piece 64 shown in Figure 5. The indicia on the indicating discs 81 determine the flight of the respective planes. The impellers preferably move with a non-uniform or jerky motion, as does the 85 impeller of the above described embodiment, thus rendering uncertain the actuation of the 90 indicating discs.

In Figures 11 and 12 I have shown a modified form of game piece wherein the figure of the runner or other miniature form is vibrated as it moves along to simulate running or motion. The game piece has a frame 90 at the front of which is cross shaft 92 having roller surfaces 93 at each end thereof 95 and a gear wheel 94 between the rollers. Pivoted to the back of the frame 90 is a base 95 and the forward end of this base rests on the gear wheel. This base carries a toy figure 96. The gear wheel 94 engages the helical 100 impeller, and when the latter rotates the gear wheel revolves. When the gear wheel revolves the rollers 93 roll on the surface of the game board at each side of the slot to move the game piece along. The rotation of the 105 gear imparts a vertical vibrating motion to the base 95 and the figure carried thereon, thereby giving further action to the toy.

The flexible impelling means for the game 110 pieces permits of the movement of such pieces in various windings and bending pathways and with various irregularities of movement where desired. At the same time the impelling means is preferably substantially concealed.

115 The combination of the means for causing the pieces representing players to move in simulation of motions made by players in the game of baseball, the use of a ball adapted to be projected about the board and an impeller for moving the playing pieces about the bases and also for actuating an indicator produces a game having both action and interest for the players. The provision of 120 means for moving the pieces representing 125 130

players as above described in combination with an indicator actuated thereby and determining the fate of certain of the players also lends an element of interest and enjoyment to the game. This is particularly true when the players whose fate is thus determined are in turn actuated by the impeller and the impeller actuates another play indicator determining their success subsequently during the playing of the game.

10 The term "game piece," as used in its broad sense in the claims, contemplates any instrumentality used in the game, such, for instance, as the rotatable discs, and is not limited to pieces freely movable along the impeller.

15 While I have shown and described certain present preferred embodiments of the invention, it is to be understood that the same is not limited thereto, but may be otherwise embodied within the scope of the following claims.

I claim:

1. In a game, a game board having an elongated slot therein extending in at least 25 two directions, a coiled wire confined under the game board in alignment with the slot, a game piece movable along the game board having means thereon projecting through the slot and engaging said coiled wire, and means 30 for rotating the coiled wire.

2. In a game, a rotatable impeller having a substantially helical piece-engaging portion, a movable piece cooperating therewith to be moved thereby upon rotation thereof, 35 and a play indicator also cooperating with the impeller to be actuated upon rotation thereof.

3. In a game, a game board, an impeller for moving pieces along the game board comprising a flexible coil, means for rotating the coil about its axis and a toothed play indicator 40 engaging said coil.

4. In a game, a game board, an impeller for moving pieces along the game board comprising a flexible coil, means for rotating the coil about its axis, and a toothed play indicator 45 engaging said coil at a plurality of points about the periphery of said indicator.

5. In a game, a game board, an impeller for moving pieces along the game board, comprising a flexible coil, means for rotating the coil about its axis, and a toothed play indicator 50 engaging said coil, said indicator having teeth of irregular pitch thereon.

55 6. In a game, a game board, an indicator, means for moving pieces about the game board comprising a flexible helix confined with relation to the game board and indicator, and means for simultaneously rotating 60 the helix about its axis and operating the indicator.

7. In a game, a rotatable impeller having a substantially helical portion and arranged in a curve, means for rotating the impeller, 85 and a loosely mounted rotatable play indi-

cator having unequally spaced teeth disposed within the curve of the impeller and in engagement therewith at more than one point whereby the indicator will be non-uniformly rotated upon uniform rotation of the impeller.

8. In a game simulating baseball, a diamond, a rotatable impeller having a substantially helical portion disposed substantially at the base paths of the diamond for moving playing pieces therearound, and playing pieces having means engaging the impeller whereby movement of the impeller causes motion of the playing pieces.

9. In a game simulating baseball, a diamond, a rotatable impeller having a substantially helical portion disposed therearound for moving playing pieces and a play indicator disposed within the diamond and actuated by the impeller.

10. In a baseball game, a mechanism for effecting movement of certain players indicating one of two opposing teams, means for effecting movement of certain players of the other of the two opposing teams, an indicator operated by said mechanism for determining the initial operation of said means, and an indicator operated by said means for determining the extent of movement thereof.

11. In a baseball game, a game board having a diamond track thereabout in the form of a slot, a coiled wire confined under the game board in alignment with the slot, means for rotating the coil, game pieces having means thereon engaging the coil by means of which they are moved around the diamond upon rotation of the coil, and an indicator operated by the coil for determining the extent of movement of the players upon each play.

12. In a baseball game, a game board having a diamond track thereabout in the form of a slot, a coiled wire confined under the game board in alignment with the slot, means for rotating the coil, game pieces having means thereon engaging the coil by means of which they are moved around the diamond upon rotation of the coil, an indicator operated by the coil for determining the extent of movement of the players upon each play, other players indicating a pitcher and a catcher, and means for effecting movement of the pitcher and catcher.

13. In a game simulating baseball, pieces representing a pitcher, batter and catcher, respectively, a single operating means for causing all of such pieces to make representative movements, and an indicator actuated by such operating means for determining the play of the batter.

14. In a game simulating baseball, pieces representing players, means for causing a plurality of such pieces to make representative movements, indicating means operated

thereby, a rotatable impeller having a substantially helical portion for moving other pieces, and pieces having means engaging the impeller whereby movement of the impeller causes motion of such pieces, the indicating means determining the operation.

15. In a game simulating baseball, pieces representing players, means for causing at least one of such pieces to make a representative movement, indicating means actuated thereby, a rotatable impeller having a substantially helical portion for moving pieces, and an indicator actuated by the impeller.

16. In a game simulating baseball, a diamond, a rotatable impeller having a substantially helical portion disposed there-around for moving playing pieces, and a play indicator having unequally spaced teeth in engagement with the impeller whereby the indicator will be non-uniformly actuated upon rotation of the impeller to move the pieces uniformly.

17. The combination with a game board having a slot therein with a flexible helical wire confined under the board along the slot, of a game piece adapted to be moved over the game board along the slot, said game piece having a roller adapted to engage the board at least one side of the slot and having a gear wheel connected with the roller adapted to engage said helical wire, said game piece having a pivoted base member adapted to rest on the gear wheel and be vibrated thereby.

In testimony whereof I have hereunto set my hand.

OTTO A. DRENGWITZ.
